TELEPHONE REPEATER

Filed Feb. 24, 1932

UNITED STATES PATENT OFFICE

JAMES P. LOWE, OF LIMA, PERU

TELEPHONE REPEATER

Application filed February 24, 1932, Serial No. 594,836, and in Great Britain January 30, 1931.

This invention relates to improvements in telephone repeaters and has for its primary object to provide a system whereby speech signals may be amplified in either direction 5 on a long-distance line without interaction between the up and down sides.

In the general system of repeaters at present in use, the repeater consist of two line balances and the repeater proper, one line balance being connected to either half of the line, and the repeater arranged so that speech currents amplified divide equally between the balance and the line, and by a differential arrangement of coils render the incoming 15 signals inoperative.

Such an arrangement, however, is dependent on an accurate balance between the line and line balance, thus making repetition on overhead lines very difficult, due to the variable 20 conditions, particularly with long-distance lines.

The invention provides an arrangement of 25 transformers, so arranged and connected that speech signals may be amplified in either direction on a long-distance line without interaction between up and down sides, and according to the invention speech currents on one side of the repeater are received by a transformer comprising two bridges, each 30 bridge being divided into two arms, each arm consisting of a primary and associated secondary winding. One arm in each bridge is arranged to neutralize the corresponding arm in the other bridge, to balance unwanted 35 speech currents, the other two arms being arranged to pass the speech currents via a suitable transformer or transformers to the amplifying device. Identical transformer arrangements are provided on both sides of 40 the repeater so that the device functions either way.

The amplified currents are passed via suitable 45 output transformer to both bridges of the transformer on the other side of the repeater, the current dividing equally between the four arms, two of which neutralize each other, the other two sending the amplified speech currents to the line.

When speech is being received, the bridge 50 is out of balance to the input transformer,

thus allowing speech currents to pass to the input transformer. When, however, amplified currents are passed to the line, the bridge is perfectly balanced to the input transformer, therefore no interaction can take place 55 between the up and down sides of the repeater.

The repeater is not balanced to the lines on either side, the balancing action functioning 60 purely within the repeater, and is quite independent of the length of line on either side of the repeater.

For a ready understanding of the invention, reference will now be made to the accompanying drawing, wherein:—

Figure 1 is a diagrammatic view of the circuit arrangement of a repeater in accordance with one practical embodiment of the invention; and

Figure 2 is a fragmentary view similar to Fig. 1 illustrating an alternative circuit arrangement.

Referring to the drawing, the transformer system in one arrangement comprises four 70 transformers having primaries a , x , x' , a' , and their associated secondaries as , xs , $x's$, $a's$, of which a and x are in one part of the system and a' and x' in the other part. The primaries x' and a' are connected in such manner that input currents in these two windings produce E. M. F.'s in their secondaries of opposing directions so that no current is produced in the secondary circuit of this part of the transformer system. On the other hand, primaries a and x are connected in such manner that input currents produce assisting E. M. F.'s in the secondary circuit of this part. The current in this secondary circuit passes to four primary 80 windings b of an auxiliary transformer. A 85 second auxiliary transformer having four primary windings b' is connected to windings $x's$, $a's$.

Four secondary windings bs and $b's$ are 90 inductively coupled to the primary coils b , b' and connected in series with a resistance c' across which the primary of an input transformer c is connected, the secondary of which is connected to an amplifying equipment, such as is usually used in current 95 100 repeaters.

peater practice. Preferably, four suitable relays, such as thermionic valves, are employed in said amplifier.

On the other side of the amplifier, an identical transformer system to that before-mentioned is provided.

The speech currents, after amplification, pass to the primary coils of output transformers e , the secondary coils of which are connected to the primary coils of transformers b , b' . The secondary winding of one transformer e is connected to the mid-points of the primary windings of transformer b so that current in one pair of the primary windings tends to induce secondary currents in the associated secondary in opposite direction to that which current in the other pair of the primary windings tends to produce in the other secondary. The same applies to the other transformer e . The amplified currents which have divided through the primary sections of b pass through secondaries as and as' and the current in each of these two windings produces an E. M. F. in its associated primary. These two E. M. F.'s are opposite in sense and therefore no current is produced. The same applies as regards secondaries $a's$ and $a's'$, that is each produces an E. M. F. in its associated primary. Due, however, to the manner in which primaries a' and a' are connected these E. M. F.'s assist each other and amplified current passes to line.

Speech currents before amplifications pass from the line through a transformer having windings P , S to the transformer primary windings a , x , x' , a' . The current flowing in the primary windings a and x induce voltages in their respective secondary windings which oppose each other in the circuit including the four windings, b , b , b , b , so that no exciting current flows through these windings, hence no voltage is induced in the secondary windings bs , bs . Now currents flowing through primary windings x' , a' induce voltages in their secondary winding $a's$ and $a's'$ which aid each other in the circuit including the primary windings b' , b' , b' , b' and the current which flows therethrough induces aiding voltages in the secondary windings $b's$, $b's$ and these voltages in turn cause current to pass through the circuit including the said resistance CI and primary c of the input transformer whereby they are delivered to the amplifying equipment.

In an alternative arrangement, as illustrated in Fig. 2 of the drawing, primaries x and x' , and secondaries as and $a's$ constitute one transformer having a common core and a' , as , $a's$ may also constitute one transformer or may be two transformers. In this case, it is necessary to reverse the direction of secondary $a's$ with reference to the two lower windings b' , as illustrated in Fig. 2 of

the drawing. It is also necessary to reverse the direction of the secondaries $b's$ with reference to the secondaries bs , that is the lower end of the lower $b's$, is connected to the lower end of the lower bs .

In this arrangement, input current in primaries a and a' produce current in their respective secondaries but, owing to the manner in which primaries x and x' are connected, these latter are unable to produce any flux in the core. The secondaries as and $a's$ act merely as dead resistance to the current in as and $a's$ respectively. The currents pass through primaries b and b' respectively and produce currents in the secondaries bs , $b's$, these currents passing to the amplifying device. The speech currents, after amplification pass, as before, to transformers e and tend to induce secondary currents in opposite directions in the secondary windings bs , $b's$. The amplified currents, which have divided through the primary systems of b , pass through secondaries as and as' , $a's$ and $a's'$. The currents in as and $a's$ tend to produce opposing fluxes in their common core with the result that no flux is produced and consequently no currents are produced in primaries x and x' . The currents in secondaries as and $a's$ are able, due to the manner in which $a's$ is connected with regard to as , to produce currents in the primaries a and a' , these currents being in phase and therefore passing to line.

Having now particularly described and ascertained the nature of my said invention and in what manner the same is to be performed, I declare that what I claim is:—

1. In telephone repeaters, the provision of a transformer comprising two bridges, each bridge being divided into two arms, each arm consisting of a primary and associated secondary winding, one arm in each bridge being arranged to neutralize the corresponding arm in the other bridge, to balance unwanted speech currents, the other two arms being arranged to pass incoming speech currents via an input transformer to an amplifying device.

2. In telephone repeaters, the provision of a transformer comprising two bridges, each bridge being divided into two arms, each arm consisting of a primary and associated secondary winding, one arm in each bridge being arranged to neutralize the corresponding arm in the other bridge, to balance unwanted speech currents, the other two arms being arranged to pass incoming speech currents via an input transformer to an amplifying device, an intermediate transformer for each bridge consisting of two pairs of primary windings, the two windings of each pair being arranged in series, one pair being connected to one side of each secondary arm of the bridge, and the other pair being connected to the remaining side of said sec-

ondary arms so that all are connected in series, a pair of secondary coils for each bridge coupled to the said primary windings, said secondary coils of the two 5 bridges being connected in series with one another and with the primary of the input transformer and output transformer for each bridge, the secondary of which has its respective sides connected to the centres of 10 the pairs of primary windings of the intermediate transformer, the primaries of said output transformers being connected in series in the output circuit of the amplifier.

3. In telephone repeaters according to 15 claim 1, the provision at each side of the repeater of a transformer interposed between the two bridges and the line, the windings of which have an impedance matched to that of the bridges and line respectively.

20 4. In a telephone repeater according to claim 2, the provision at each side of the repeater of a transformer interposed between the two bridges and the line, the windings of which have an impedance matched to that 25 of the bridges and line respectively.

5. A signal transmission system comprising two one-way paths, a two-way path and 30 means for joining said one-way paths electrically to said two-way path and for rendering them electrically independent, said means comprising a plurality of transformers having their primaries connected to the two-way path and their secondaries connected through balanced circuits to the one- 35 way paths.

6. In telephone repeaters, a transformer system divided into two parts, each part having two primary windings and two secondary windings, the primary windings being so arranged with reference to each other and to 40 their associated secondary windings that input speech currents in two of the primary windings produce no currents in their associated secondaries and that amplified speech 45 currents in two of the secondary windings produce no currents in their associated primary windings.

7. In telephone repeaters, a transformer system divided into two parts each part having two primary windings and associated secondary windings, one primary of one part being so arranged with reference to the other primary of the same part and to their associated secondaries that currents in the said 55 two primaries produce no currents in the said secondaries, the two primary windings of the other part being so arranged with reference to each other and their associated secondaries that currents in the said two primaries produce currents in their associated 60 secondaries.

8. In telephone repeaters, a transformer system divided into two parts each part having two primary windings and associated secondary windings one primary of one part be- 65

ing so arranged with reference to one primary of the other part and to their associated secondaries that currents in the said two primaries produce no currents in the said two secondaries, the other primary windings of 70 the two parts being so arranged with reference to their secondaries that currents in the said other primaries produce currents in their associated secondaries.

In testimony whereof he hereunto affixes 75 his signature.
